EDWARD J. JACKOBOICE, OF GRAND RAPIDS, MICHIGAN

HYDRAULIC SCRAPER

Application filed February 23, 1929. Serial No. 341,902.

This invention relates to hydraulic operating and control mechanism for road scraper blades and the like adapted to be mounted on a motor truck.

5 The main objects of this invention are to provide an improved control and operating unit of the hydraulic type for a highway scraper blade; to provide a hydraulic operating unit which is extremely simple in construction with a minimum of moving parts; and, to provide such a unit that will give long and satisfactory use with a minimum of upkeep and expense.

An illustrative embodiment of this invention is shown in the accompanying drawings, in which:

Fig. 1 is a view in rear elevation of my improved device mounted on the chassis frame of a motor truck, a portion of the 20 scraper blade being broken away to more clearly show the operating mechanism.

Fig. 2 is an enlarged transverse sectional view taken at the medial part of Fig. 1, with the scraper blade swung rearwardly to substantially its limit of movement.

Fig. 3 is a view similar to Fig. 2 but with the hydraulic cylinder shown in section and with the scraper blade partially rotated to an upright position.

30 Fig. 4 is an enlarged fragmentary plan view of the medial portion of Fig. 1 with the supporting beam and bracket partially broken away to show the trunnion mounting of the hydraulic cylinder.

35 In the construction shown in the drawings, a supporting beam 1 in the form of a heavy channel iron is shown mounted to the chassis frame 2 of a motor truck or the like by means of brackets 3, with the channel facing downwardly, that is, with the flanges of the channel iron depending from the web. This supporting beam 1 may be mounted on the truck chassis so as to be horizontally swingable on a vertical axis if desired, such swingable mounting being common in the art and is for the purpose of varying the angle of the scraper blade with relation to the highway when the truck upon which it is mounted is being driven parallel to such highway.

The medial portion of the supporting beam 1 is provided with a transversely disposed bracket arm 4 riveted or otherwise rigidly fastened thereto and which has a forwardly extending arm 5, the outer end of which has 55 depending arms 6. The arms 6 support a pivot pin 7 whose axis is substantially parallel to the longitudinal axis of the supporting beam 1.

The lower side of the supporting beam 1 60 has the upper ends of a plurality of depending brackets 8 bolted or otherwise rigidly secured thereto. The lower ends of the brackets 8 are provided with bearings 9 the axes of which are in alignment and in which is 65 journaled a rock shaft 10 in spaced parallel relation to the supporting beam 1.

Near its medial portion, the rock shaft 10 is provided with a pair of spaced parallel upstanding arms 11 rigidly mounted thereon 70 the upper ends of which pivotally support transversely disposed trunnions 12 and 13 integrally formed on diametrically opposite sides of a hydraulic cylinder 14.

The front end of the hydraulic cylinder 75 14 is provided with a packing gland 15 through which slidably passes a piston rod 16, the inner end of which rigidly carries a piston 17. The outer end of the piston rod 16 is provided with a bearing 18 which 80 receives the pivot pin 7.

In order to conserve space and secure compactness of the unit, the depending flanges of the supporting channel beam 1 are cut away adjacent the hydraulic cylinder when 85 mounted in close relation to said supporting beam. The end of the hydraulic cylinder 14 opposite to the packing gland 15 is provided with a hydraulic connection 19 to which is secured the customary flexible hydraulic hose 90 20 by which fluid may be introduced into the cylinder 14 back of the piston 17 for the purpose of causing a relative movement between the piston and cylinder.

The rock shaft 10 is also provided with a 95 plurality of short arms 21 rigidly secured thereto, the outer ends of which pivotally support the upper ends of scraper blade supporting arms 22 upon which a scraper blade 23 is rigidly mounted.

The scraper blade 23 is resiliently held in a normal position with respect to the rocker arm by means of compression springs 24 and 25 respectively. The compression springs 24 and 25 surround a rod 26 one end of which is mounted on lugs 27 secured to the rocker arm 10, the other end of which is provided with a washer 28 and nut 29. The spring 25 bears between the washer 28 and the rear face of the arm 22. The spring 24 bears between the front face of the arm 22 and the lugs 27.

Means are provided for normally rotating the scraper blade rearwardly and upwardly and comprise a pair of tension springs 30 and 31, each of which has its lower end secured to bracket clips 32 and 33 respectively which are secured to the rear face of the scraper blade 23. The upper ends of said springs are secured to the upwardly and rearwardly extending ends of brackets 34 and 35 respectively which are secured to the upper side of supporting beam 1.

In the operation of this device, the supporting beam 1 is secured to the chassis frame of a motor truck, either rigidly or adjustably as desired, and the flexible hydraulic hose 20 is attached to the discharge end of a suitable hydraulic pump unit. When there is no pressure in the hydraulic cylinder, the tension springs 30 and 31 draw the scraper blade 23 upwardly and rearwardly as shown in Fig. 2 of the drawings so as to have clearance with respect to the roadway over which the motor truck is travelling.

When it is desired to bring the scraper blade 23 in contact with the highway, the hydraulic pump is operated and fluid pumped into the hydraulic cylinder 14 through the flexible hydraulic hose 20 and connection 19. Introduction of the fluid into the cylinder 14 causes relative movement between the cylinder and the piston 17. The piston rod 16 which supports the piston 17, being pivotally connected to the rigidly mounted bracket 4, causes the hydraulic cylinder 14 to move rearwardly with respect to the supporting beam 1 and through the medium of the trunnion connections 12 and 13 thus rotates the arms 11 rearwardly. Such movement rotates the rock shaft 10 which in turn swings the scraper blade 23 downwardly and forwardly into contact with the highway.

Resilient contact of the scraper blade 23 with the highway is secured by means of the compression springs 24 and 25 so that if the scraper blade should contact with a more or less rigid obstruction in the highway, the scraper blade 23 has limited rearward movement against the compression spring 25. After passing over the obstruction, the blade's forward movement is resiliently checked by coming in contact with the compression spring 24.

The vertical angle of the scraper blade

23—that is, its angle of contact with respect to the highway—may be varied by pumping more or less fluid into the hydraulic cylinder 14 thus causing a proportionate amount of relative movement between the cylinder 14 and its piston 17.

Although but one specific embodiment of this invention has been herein shown and described, it will be understood that numerous details of the construction shown may be altered or omitted without departing from the spirit of this invention as defined by the following claims.

I claim:

1. In a hydraulic road scraper construction, the combination of a supporting beam adapted to be secured to a chassis frame, a rock shaft journalled on said beam, a scraper blade carried by said rock shaft, an arm rigidly secured to said rock shaft, a hydraulic cylinder pivotally mounted on said arm, a piston in said hydraulic cylinder and a piston rod having one end secure to said piston and its other end secured to said supporting beam.

2. In a hydraulic road scraper construction, the combination of a supporting beam adapted to be secured to a chassis frame, a bracket arm rigidly secured to and disposed transversely of said supporting beam, a bearing on the outer end of said arm, a rock shaft journalled on said beam, a scraper blade carried by said rock shaft, an arm rigidly secured to said rock shaft, a hydraulic cylinder pivotally mounted on said arm, a piston in said hydraulic cylinder and a piston rod having one end secured to said piston and its other end secured to said arm bracket.

3. In a hydraulic road scraper construction, the combination of a supporting beam adapted to be secured to a chassis frame, a bracket arm rigidly secured to and disposed transversely of said supporting beam, a bearing on the outer end of said arm, depending brackets on said beam, a rock shaft journalled on the lower ends of said depending brackets, a scraper blade resiliently carried by said rock shaft, a rocker arm on said rock shaft, a hydraulic cylinder pivoted to said rocker arm, a piston in said cylinder, a piston rod connecting said piston and said beam bracket arm bearing, and means for introducing fluid into said cylinder for causing relative movement between said cylinder and piston to vary the angle of contact of said scraper blade.

4. In a hydraulic road scraper construction, the combination of a supporting beam adapted to be secured to a chassis frame, depending brackets on said beam, a rock shaft journalled on the lower ends of said depending brackets, a scraper blade carried by said rock shaft movable therewith, upwardly extending trunnion bearings on said rock shaft, a hydraulic cylinder embraced by said bear-

ings, diametrically-opposed outwardly-extending trunnions on said hydraulic cylinder journaled in said bearings, a piston in said hydraulic cylinder, a piston rod slidable in one end of said cylinder with one end thereof secured to said piston and the other end thereof pivotally attached to said supporting beam, and means for introducing fluid in said cylinder to cause relative movement between said piston and cylinder to rock said scraper blade for varying its angle of contact with respect to a highway.

In testimony whereof I have hereunto set my hand at Grand Rapids, Michigan, this 19th day of February, 1929.

EDWARD J. JACKOBOICE.
